(57) **CLAIM**

The ornamental design for a liquid container with clock, as shown and described.

DESCRIPTION

FIG. 1 is a front perspective view of a liquid container with clock showing my new design;

FIG. 2 is a front elevational view thereof;

FIG. 3 is a back elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a front elevational view showing the practical usage thereof.

The broken line showing of a fish and water line in FIG. 8 is for illustrative purposes only and forms no part of the claimed design.
